ELMER R. CORWIN, OF CHICAGO, ILLINOIS, ASSIGNOR TO FRANK B. COOK COMPANY,
OF CHICAGO, ILLINOIS, A CORPORATION OF ILLINOIS.

TELEPHONY.

1,173,776.

Specification of Letters Patent. Patented Feb. 29, 1916.

Application filed January 15, 1915. Serial No. 2,390.

To all whom it may concern:

Be it known that I, ELMER R. CORWIN, a citizen of the United States, residing at Chicago, in the county of Cook and State of Illinois, have invented a certain new and useful Improvement in Telephony, of which the following is a full, clear, concise, and exact description, reference being had to the accompanying drawings, forming a part of 10 this specification.

My invention relates to telephone systems and has a number of objects and advantages in view.

By means of one feature of my invention 15 those regular call receiving operators that are normally available for extending calling lines and may normally be reached for this purpose by calling subscribers are replaced by special operators when lines are placed 20 out of working condition as, for example, by accidental grounds and short circuits. This feature of the invention is of service not only to guard against the extension of accidentally grounded telephone lines to regular operators but also is of service in guarding 25 against the application of regular calling line extensions to incoming ends of accidentally grounded telephone lines extending from subscribers' stations or other stations.

As I have practised the invention the regular operators are automatically replaced 30 when telephone lines are grounded and are replaced by the operation of the regular operators themselves when telephone lines are short circuited.

In accordance with the preferred embodiment of the invention the means which the regular operators employ for substituting special operators are used by the regular 35 operators also to substitute special operators for which the regular operators have insufficient or unadaptable equipment. For example, one party line subscriber may wish to converse with another subscriber upon the same line, in which case it is desirable to have the called party line subscriber signaled by equipment presided over by a special operator whereby the efficiency of the regular operator in her regular routine of extending calling telephone lines will not be impaired. Where trouble men or others may 45 wish to know the line designations of certain subscribers' telephone lines which they are using; or in the case of fire or other emergency calls, or in the case of parties who

have made improper use of telephone lines it is desirable to have the information concerning the designations of such lines brought within the knowledge of a special operator who may call back over these lines, 60 extend the same where necessary, and mention or report the designations thereof.

My invention also has for its object the provision of indicating means to denote the number of occasions and preferably the extent 65 of such occasions when the link connectors assigned to each operator or otherwise employed are all taken for use whereby by the operating manager may be guided in grouping the telephone lines to suit the capacity 70 of the operators or the capacity of the equipment of the system.

The various features of my invention are of particular service in that class of telephone exchange systems wherein the regular 75 receiving operators do not preside over signal devices that are individual to subscribers' lines, though the invention is not to be restricted in its adaptation to such telephone systems. In practising that feature of my 80 invention whereby a regular receiving operator may substitute equipment of a special operator in connection with a calling line, I desirably use a part of such calling line, or extension thereof, or the answering end of 85 the employed regular operator's link connector connected with such calling line and which itself also constitutes a calling line extension, the connecting end of the link connector or other line extension being in 90 each case excluded from the connection or connecting means whereby the special operator is reached. In the preferred embodiment of the invention the connecting means by which the special operator is reached includes a portion of the calling line, the adjacent end of the link connector and also 95 another calling line extension.

I will explain the foregoing and other features of my invention more fully by reference 100 to the accompanying drawings in which—

Figures 1 and 2, taken collectively, illustrate a telephone exchange system equipped in accordance with one embodiment of the 105 invention and Fig. 3 is a diagrammatic illustration of that feature of the invention which includes indicating mechanism for determining the frequency with which the operators' link connectors are fully taken for 110

use and the frequency of the periods of such complete use of the link connectors at the different positions.

I have shown two subscribers' telephone stations 200, 201 at each of which there is located equipment that includes a telephone switch hook 1, a telephone receiver 2, a telephone transmitter 3, a call bell 4, and a condenser 5, the switch hook being provided with a normal contact that includes the bell and condenser in bridge of the associate line when the receiver is upon the hook and an alternate contact whereby the telephone receiver and telephone transmitter are included in the line when the switch hook is free of the receiver. The limbs of each telephone line extend to the exchange, the normal circuit relation and the normal environment thereof being such that when the receiver at a calling station is removed from its switch hook a circuit is established which is traceable from the grounded common battery 6 (the illustration of this battery being repeated throughout the diagram for the sake of clearness, though it is to be understood that one battery is preferably employed), the upper armature switch of the cutoff relay 7 and its contact, both sides of the calling line, by way of the calling station, the lower armature switch of the cutoff relay and its contact, to the grounded winding of the line relay 8. The line relay is thereupon energized to establish a circuit traceable from the grounded battery 6 through the winding of the individual switch starting relay 9 (that pertains to a master switch common to a number of link connectors), the upper armature switch of the master switch driving relay 10 and its contact, the lower armature switch of said line relay, to its then engaged and grounded contact. The starting relay 9, being energized, attracts its armature switch to establish a circuit traceable from the grounded battery 6, the winding of the individual switch motor magnet 11, (there being one such motor magnet together with its switch for each link connector) its make and break armature switch which is also the actuating armature of the motor magnet 11, the waiting contact 12 individual to the magnet 11, the wiper 13 of the illustrated master switch, the armature switch of the individual switch motor magnet controlled relay 14 and its normal contact, the attracted armature switch of relay 9 to its then engaged and grounded contact. It is understood that the similarly positioned waiting contacts of the individual electro-magnetic switches belonging to the magnets 11 of a group are in multiple connection. If the wipers 15, 16, 17 and 18 of the employed individual electro-magnetic switch do not happen to be resting in contact with waiting contacts pertaining to the calling line

the magnet 11 is set into operation until these wipers engage such contacts whereby the motor magnet 11 is deenergized to permit these wipers to remain in association with the calling line, this result being due to the operation of the armature switch of relay 14 which in turn is due to the then established circuit through the relay 14 traceable from the grounded battery 6, the winding of this relay, the wiper 19 of the master switch, the waiting contact engaged by this wiper and individual to the individual motor switch, the wiper 18 of this switch, the waiting contact engaged by this wiper and individual to the calling line, the upper armature switch of the line relay 8, to its then engaged and grounded contact. Obviously if the wiper 18 happens to be in engagement with a waiting contact that belongs to the calling line the relay 14 will be instantly energized so that the motor magnet 11 will not operate. The opening of the circuit of the motor magnet 11 at the armature switch of the relay 14 is followed by the closure of another circuit due to the movement of this armature switch into engagement with its alternate contact, and which new circuit is traceable from the grounded battery 6, through the upper winding of the calling transmitter battery relay 20, the wiper 21 and its waiting contact pertaining to the master switch, the armature switch of the relay 14 and its engaged alternate contact, the armature switch of relay 9, to its grounded contact. The armature switches of relay 20 are now attracted, the two topmost armature switches of this relay engaging their contacts to complete the contacting strands of the employed link connector or line joining calling line extension whose answering end terminates in the wipers 15, 16 and whose connecting end is shown in the form of a connecting plug 27' but to which form of connecting end for the link connector or line extension the invention is not to be limited. The armature switch of the relay 20 which is illustrated immediately above the core of this relay is now included in a circuit traceable from the grounded common battery 6 through the winding of the cutoff relay 7, the wiper 17 of the employed individual electro-magnetic switch and the waiting contact engaging the same and which pertains to the calling line, the armature switch of the special operator's calling relay 23 that is illustrated immediately above the core of this relay, the normal contact of this armature switch, to the aforesaid and grounded armature switch of the relay 20 and its then engaged contact. The cutoff relay 7 is thus energized to attract its armature switches and open circuit for the associate line relay 8 whereupon the armature switches of this line

relay are separated from their grounded contacts to open circuit for the relays 9 and 14 whereby these relays restore their armature switches to normal.

5 When the relay 20 was energized a circuit was established at its lowermost armature switch traceable from the grounded battery 6, the master switch driving relay 10, the wiper 24 of the associate master switch and 70 the waiting contact engaging the same, the said lowermost switch of the calling transmitter battery relay 20 and its engaged alternate contact, to the grounded lowermost armature switch of the special operator calling relay 23 and its normal contact. When 75 the relay 10 is energized it opens the circuit of the individual switch starting relay 9 which is common to all of the motor magnets 11 of a group whereby no other calling line may have access to any motor magnet 11 of the group to which the relay 9 is common until the relay 10 is again deenergized. After the employed motor magnet 11 has become associated with the calling line the 80 master switch having the wipers 13, etc., and which is common to a group of motor magnets 11, is operated to predetermine the next motor magnet 11 which is to be operated to connect another calling line with another one of the group of link connectors 85 having the group of magnets 11. To this end the motor magnet 25 pertaining to the master switch is now included in a circuit which is traceable from the common grounded battery 6, the winding of the motor magnet 25, the lower armature switch of the now energized relay 10, the right hand pair of contacts of the button 26 individual to some idle link connector or a number of 90 such pairs of contacts in multiple, the middle armature switch of the called transmitter battery relay 27 of an idle link connector and the contact engaging this switch, the lowermost armature switch of the relay 20 of an idle link connector and the normal contact of this switch, to the bottom and grounded armature switch of the relay 23 of such idle link connector by way of the normal contact of this armature switch. The magnet 95 25 will continue in operation until the wiper 24 engages a waiting contact pertaining to some unemployed link connector from which ground is removed by the operation of a relay or relays of such unemployed link connector. The motor magnet 25 is now 100 brought to rest with its associate wipers of the master switch in association with some idle motor-magnet 11 which will be the next to be employed when a new call is initiated by a calling subscriber. When all of the motor magnets 11 of a group have been taken for use to extend calling lines the motor magnet 25 of the master switch common to the magnets 11 of their group will not operate 105 owing to the energized condition of relays 110 belonging to the link connectors having such motor magnets 11. The wipers of the master switch will then remain in association with waiting contacts individual to the last link connector taken for use, at which time the relay 10 is energized to close the adjacent gap in the circuit of the motor magnet 25 to place the motor magnet in condition for immediate operation when any of the link connectors have been restored to normal, 115 whereupon the wipers of the master switch will seek the first idle link connector if they do not already rest upon waiting contacts individual thereto. The buttons 26 are only to be manipulated when the link connectors 120 to which they are individual are to be thrown out of service or made artificially busy whereby each operator may have apportioned to her the number of link connectors which she is adapted efficiently to handle. When a button 26 is depressed for this purpose the contacts of the right hand pair are separated and the contacts of the left hand pair are connected, the first, effect being to prevent the closure of circuit 125 for the motor magnet 25 by way of apparatus pertaining to the abandoned link connector and the second effect being to place ground upon the waiting contact individual to the abandoned link and engaged by the wiper 24 of the master switch to prevent the master switch from stopping upon this link when the master switch is operating. The master switch now having been disconnected from the employed link connector, 130 transmitter battery current is furnished to the calling line by way of the windings of the calling transmitter battery relay 20 of the link connector now joined with the calling line, between which windings the battery is included and with which windings it is in bridge of the talking strands or sides of the employed link connector. The operator's telephone outfit 28, details of which obviously do not have to be described, is common to the link connectors or line extensions of a group adapted for interchangeable connection with calling and called lines and may have association with any link connector which is taken for use 135 by means of the listening key 29 individual to such link connector. The operator knows which listening key to depress by the presentation to view of a signal 30 that is operated by the relay 20. After such listening key has been depressed the operator is in telephonic connection with the calling subscriber and will, after the usual test, engage the connecting end or plug 27' of the employed link connector with the jack or other switch 31 pertaining to the wanted line, assuming that the service desired by the calling subscriber is of an ordinary nature. Transmitter battery is furnished 140 to the called party by way of the windings 145

of the associate called transmitter battery relay 27 between whose windings the common battery 6 is included and together with which windings it is in bridge of the strands 5 of the employed link connector. The link connector is shown as being divided into answering (left hand) and called (right hand) sections or ends by means of the condensers 32.

10 If the calling subscriber should desire some service which is not within the scope of the regular receiving operator's duty or is not within her capacity to perform, such regular operator will depress the button 33 individual to the link connector that now joins the calling subscriber with this regular operator to close a gap in the circuit which includes an interrupter 34, the grounded common battery 6, the resistance 35, say of 20 five hundred ohms, and the winding of the associate special operator calling relay 23, which is sluggish in release. When the relay 23 has been energized it presents a signal 36 to view, whereupon the operator 25 may release the depressed button 33, the circuit of the relay 23 being maintained, due to the sluggishly releasing action thereof, by means of a circuit traceable from the grounded battery 6, the cutoff relay 7, the 30 wiper 17 and its engaged waiting contact, the armature switch and relay 23 that is shown immediately above its core, the alternate contact of this armature switch, the winding of this relay to the grounded 35 interrupter 34. As the cutoff relay 7 is quick to respond while the relay 23 is slow to release, the armature switches of relay 7 will vibrate while the armature switches of the relay 23 will remain attracted during the 40 circuit openings effected by the interrupter 34 whereby the common grounded battery 6, in addition to being included in the circuit just traced, is also intermittently included in circuit with a line lamp 37 appearing before 45 the special operator and individual to the calling line, each line having an individual signal or line lamp before its operator. The stated arrangement of the lamps or other operator's responsive devices 37 is preferred but I do not wish to be limited to the use of responsive devices 37 that are individual to the subscriber's lines nor to the nature of such responsive devices. The circuit just intermittently established for this lamp is 50 traceable from the common battery 6, the lamp individual to the calling line that desires special service, the upper armature switch of the cutoff relay 7 individual to this calling line, the contact engaged by this 55 armature switch, the talking wiper 15, the topmost armature switch of the energized relay 23, to the grounded and alternate contact of this switch. The energized relay 23 in addition to operating the signal 37 individual to the calling subscriber that desires

special service and which appears before the special operator, also opens the circuit for the relay 20 to restore the calling signal 30 to normal, this relay 23 also adjusting the circuit condition pertaining to the master 75 switch to prevent the master switch from stopping upon the associate link during the time the relay 23 of such link is energized. The special operator, in response to the signal conveyed to her by the intermittently 75 flashing lamp 37 that is individual to the calling subscriber desiring special service will extend her telephone outfit 38 into connection with such calling line by means of some suitable switching appliance such as 80 an answering plug 39 inserted within a multiple jack 40 pertaining to the calling subscriber and by the depression of a listening key 41 if such be employed. When the plug 39 is first inserted within such jack 40 85 a shunt is established about the relay 23 of the employed regular operator's link connector which is traceable from the grounded calling supervisory relay 42, say of twenty ohms resistance, the heel of the answering 90 plug 39, the thimble of the jack 40, the cutoff relay 7, of say five hundred ohms, to the grounded battery 6, the associated relay 23 being thereupon deenergized as it is of, say one thousand ohms resistance. The armature switches of the relay 23 are now restored to normal and the associate link connector is placed in condition where it may again become appropriated by the master 95 switch for connection with a calling line. The special operator, being now in communication with the calling subscriber who desires special service, will respond to the inquiries of the calling subscriber and thereafter withdraw the answering plug 39 if 100 this is all of the service which the calling subscriber wishes. If, however, the calling subscriber should desire connection with another subscriber upon the same line with him, assuming that the calling line is a party line, the special operator will withdraw the answering plug 39 from the calling subscriber's jack 40 after having requested the calling subscriber to hang up his receiver, whereafter she will insert the connecting plug 43 in the jack 40 of the party line and ring the calling and called parties 115 upon the party line by properly including the calling generator 44 in circuit with such line with the aid of the ringing key 45. If, however, the calling subscriber, having had certain peculiar inquiries answered, should wish connection with another subscriber upon a different line, the answering plug 39 will remain in its original connection and the plug 43 will be inserted within the jack 40 of such other line after it is tested and is found idle, the generator 44 again being brought into circuit to signal the called party. The link connectors presided over by 120 125 130

the special operator and including the plugs 39 and 43 may be of any suitable and preferred kind and a detail description thereof will not be necessary, it being sufficient to add that there is illustrated a called supervisory relay 46.

One of the cases of trouble, and which is to be corrected with the aid of a special operator, is that which arises when a shunt 10 (such as is indicated by the dotted line 47) is accidentally placed across the sides of a telephone line, the shunt being followed by the connection of a regular operator with such line in the manner which has hitherto been described, since the accidental shunt 15 performs a calling line extending function that is performed by the subscriber's telephone bridge when it is completed across a calling line. When the selected regular operator 20 answers the supposedly incoming call and gets no response she substitutes the equipment of the special operator for her own equipment in the manner which has been specified.

25 Where a ground, such as is indicated by the dotted lines 48, accidentally occurs upon one side of a subscriber's line, the signal lamp 37 individual to such line and appearing before the special operator is caused 30 steadily to glow, this lamp being included in a circuit traceable from the grounded battery 6, the lamp 37, the upper armature switch of the cutoff relay 7, and its contact, to the ground 48. If the grounded connection 35 indicated at 49 is placed upon the other side of a subscriber's line said lamp 37 will be caused steadily to glow when the receiver 2 at the corresponding substation is removed from its hook, circuit being established 40 traceable from the grounded battery 6, the lamp 37, the upper armature switch of cutoff relay 7 and its engaged contact, the telephone bridge at the corresponding subscriber's station, to the ground 49. The special operator will first attend to those lines 45 which grounds have occurred as indicated by the steadily glowing lamps. As the invention is preferably practised the signal lamps 37 do not glow unless the lines to which they are individual are accidentally 50 grounded or unless they are caused to glow by a regular operator. When a calling subscriber's line is grounded upon either side the associate line relay 8 is shunted so that it will not operate whereby a regular receiving operator cannot be selected and her equipment cannot be tied up during the impaired condition of such subscriber's line. This feature of the invention obviously is 55 of service not only to guard against the 60 tension of accidentally grounded telephone

lines to regular operators but also is of service in guarding against the application of regular calling line extensions to accidentally grounded lines and this feature of the invention is not therefore to be limited to 70 a telephone exchange system in which operators normally take part in extending normal calling telephone lines.

Referring now more particularly to Fig. 3, though Fig. 1 may also be referred to, I 75 have illustrated two groups of link connectors each having connecting plugs 27' at different operators' positions. The magnets 27 belonging to each group of link connectors have their bottom armature switches 80 included in serial relation in a circuit which includes an indicator operating magnet *a*, each group of link connectors having a magnet *a* individual thereto. The indicating instrument of which the magnet *a* forms a 85 part may include a suitable record receiving element such as the recording drum indicated at *b* revolved at a uniform rate of speed to enable the magnet *a* to apply the recording pen *c* thereto when all of the magnets 90 27 to which the relay *a* is common are energized, the magnet *a* remaining in open circuit when any of the relays 27 of the group to which it belongs is deenergized. Thus the magnet *a* common to the link connectors of a group is inactive when there is 95 any link connector of such group that is not employed but remains active to make a record whenever all of the magnets 27 of the group to which it belongs are energized. 100 If an indicator *b* should show that the link connectors in a group to which such indicator is individual are too frequently completely employed or are completely employed for periods of time that are too long, 105 the number of telephone lines assigned to the operator having such links may be reduced by having some of them transferred to another operator whose indicator *b* would show that such transfer could be permitted. 110 The usual transfer board *d* may, of course, be employed in effecting the desired redistribution.

While I have herein shown and particularly described the preferred embodiment 115 of my invention I do not wish to be limited to the exact details of construction and circuit arrangement shown as changes may readily be made without departing from the spirit of my invention, but

Having thus described my invention I claim as new and desire to secure by Letters Patent the following:

1. A telephone exchange system including telephone lines extending to an exchange; 125 line extensions for interchangeable connection with the incoming ends of such lines in the normal operation of the exchange; other telephone line extensions that are to be excluded from connection between 130

calling and called lines in the normal operation of the system; and operator's responsive devices associated with these latter extensions and having means whereby they 5 are unresponsive to telephone lines in normal condition and are responsive to telephone lines in abnormal condition.

2. A telephone exchange system including telephone lines extending to an exchange; 10 line extensions for interchangeable connection with the incoming ends of such lines in the normal operation of the exchange; other telephone line extensions that are to be excluded from connection between calling 15 and called lines in the normal operation of the system; and responsive devices associated with these latter extensions and having means whereby they are unresponsive to telephone lines in normal condition and 20 are responsive to telephone lines in abnormal condition.

3. A telephone exchange system including telephone lines extending to an exchange; 25 line extensions for interchangeable connection with the incoming ends of such lines in the normal operation of the exchange; other telephone line extensions that are to be excluded from connection between calling and called lines in the normal operation 30 of the system; and operator's responsive devices, individual to the telephone lines, associated with these latter extensions and having means whereby they are unresponsive to telephone lines in normal condition 35 and are responsive to telephone lines in abnormal condition.

4. A telephone exchange system including telephone lines extending to an exchange; 40 line extensions for interchangeable connection with the incoming ends of such lines in the normal operation of the exchange; other telephone line extensions that are to be excluded from connection between calling and called lines in the normal operation of 45 the system; and responsive devices, individual to the telephone lines, associated with these latter extensions and having means whereby they are unresponsive to telephone lines in normal condition and are responsive to telephone lines in abnormal condition.

5. A telephone exchange system including telephone lines extending to an exchange; 50 line extensions for interchangeable connection with the incoming ends of such lines in the normal operation of the exchange; other telephone line extensions that are to be excluded from connection between calling and called lines in the normal operation 55 of the system; and operator's responsive devices associated with these latter extensions and having means whereby they are responsive to telephone lines in normal condition and are responsive to accidentally 60 grounded telephone lines.

6. A telephone exchange system including telephone lines extending to an exchange; line extensions for interchangeable connection with the incoming ends of such lines in the normal operation of the exchange; 70 other telephone line extensions that are to be excluded from connection between calling and called lines in the normal operation of the system; and responsive devices associated with these latter extensions and having means whereby they are unresponsive to telephone lines in normal condition and are responsive to accidentally grounded telephone lines.

7. A telephone exchange system including 75 telephone lines extending to an exchange; line extensions for interchangeable connection with the incoming ends of such lines in the normal operation of the exchange; other telephone line extensions that are to be excluded from connection between calling and called lines in the normal operation 80 of the system; and operator's responsive devices, individual to the telephone lines, associated with these latter extensions and having means whereby they are unresponsive to telephone lines in normal condition and are responsive to accidentally grounded 85 telephone lines.

8. A telephone exchange system including 90 telephone lines extending to an exchange; line extensions for interchangeable connection with the incoming ends of such lines in the normal operation of the exchange; other telephone line extensions that are to be excluded from connection between calling and called lines in the normal operation 95 of the system; and responsive devices, individual to the telephone lines, associated with these latter extensions and having means whereby they are unresponsive to telephone lines in normal condition and are responsive to accidentally grounded 100 telephone lines.

9. A telephone exchange system including 105 telephone lines extending to an exchange; line extensions for uniting lines in conversation and in interchangeable association with the incoming ends of telephone lines to effect the extension of these lines to a regular operator's position; other line extensions 110 pertaining to a special operator's position for uniting lines in conversation and in interchangeable association with the incoming ends of telephone lines to effect the extension of these lines; a special operator's responsive device; and means controlled by the regular operator for operating said responsive device independently of the connecting ends of the line extensions under her control and by way of the answering 115 ends of these line extensions.

10. A telephone exchange system including 120 telephone lines extending to an exchange; line extensions for uniting lines in conversation and in interchangeable association with the incoming ends of telephone lines to effect the extension of these lines; a special operator's responsive device; and means controlled by the regular operator for operating said responsive device independently of the connecting ends of the line extensions under her control and by way of the answering 125 ends of these line extensions.

the line extensions with the incoming ends of telephone lines to effect the extension of these lines to a regular operator's position; other line extensions pertaining to a special 5 operator's position for uniting lines in conversation and in interchangeable association with the incoming ends of telephone lines to effect the extension of these lines; a special operator's responsive device individual to 10 the telephone lines; and means controlled by the regular operator for operating said responsive device independently of the connecting ends of the line extensions under her control by way of the answering ends of 15 these line extensions and the incoming ends of the telephone lines and by way of employed electro-magnetic switches.

24. A telephone exchange system including telephone lines extending to an exchange; line extensions for uniting lines in conversation; electro-magnetic switches for effecting the interchangeable association of the line extensions with the incoming ends of telephone lines to effect the extension of 20 these lines to a regular operator's position; other line extensions pertaining to a special operator's position for uniting lines in conversation and in interchangeable association with the incoming ends of telephone lines to effect the extension of 25 these lines to a regular operator's position; other line extensions pertaining to a special operator's responsive device individual to the telephone lines; and means controlled by the regular operator for operating said responsive device independently of the connecting ends of the line extensions under her control by way of the incoming ends of the telephone lines and by way of employed 30 electro-magnetic switches.

25. A telephone exchange system including telephone lines extending to an exchange; a group of link connectors at the exchange for uniting lines in conversation; a master switch common to said link connectors and having related thereto means where- 40 by it will become associated with an idle link connector to predetermine it for use and will leave association with this link connector when this link connector is taken for use to become associated with a new unemployed 45 link connector; electro-magnetic switches individual to the link connectors and adapted by the master switch for operation to connect the answering ends thereof with the incoming ends of the telephone lines; and means for preventing the operation of the 50 electro-magnetic switches through the master switch when all of said link connectors have been taken for use.

26. A telephone exchange system including telephone lines extending to an exchange; a group of link connectors at the exchange for uniting lines in conversation; a master switch common to said link connectors and having related thereto means 55 whereby it will become associated with an

idle link connector to predetermine it for use and will leave association with this link connector when this link connector is taken for use to become associated with a new unemployed link connector; electro-magnetic 70 switches individual to the link connectors and adapted by the master switch for operation to connect the answering ends thereof with the incoming ends of the telephone lines; and means for preventing the opera- 75 tion of the master switch when all of the link connectors have been taken for use.

27. A telephone exchange system including telephone lines extending to an exchange; a group of link connectors at the 80 exchange for uniting lines in conversation; a master switch common to said link connectors and having related thereto means whereby it will become associated with an idle link connector to predetermine it for 85 use and will leave association with this link connector when this link connector is taken for use to become associated with a new unemployed link connector; and operator controlled means for preventing the operation 90 of the master switch when all of said link connectors have been taken for use.

28. A telephone exchange system including telephone lines extending to an exchange; line extensions for uniting lines in 95 conversation and in interchangeable association with the incoming ends of telephone lines to effect the extension of these lines to a regular operator's position; other line extensions pertaining to a special operator's 100 position for uniting lines in conversation and in interchangeable association with the incoming ends of telephone lines to effect the extension of these lines; special operator's responsive devices permanently asso- 105 ciated with the telephone lines; and means controlled by the regular operator for operating said responsive devices independently of the connecting ends of the line extensions under her control and by way of the 110 incoming ends of the telephone lines.

29. A telephone exchange system including telephone lines extending to an exchange; line extensions for uniting lines in conversation; electro-magnetic switches for effecting the interchangeable association of the line extensions with the incoming ends of telephone lines to effect the extension of these lines to a regular operator's position; other line extensions pertaining to a special operator's position for uniting lines in conversation and in interchangeable association with the incoming ends of telephone lines to effect the extension of these lines; special operator's responsive devices per- 115 manently associated with the telephone lines; and means controlled by the regular operator for operating said responsive devices independently of the connecting ends of the line extensions under her control 120

125

130

and by way of the incoming ends of the telephone lines.

30. A telephone exchange system including telephone lines extending to an exchange; line extensions for uniting lines in conversation and in interchangeable association with the incoming ends of telephone lines to effect the extension of these lines to a regular operator's position; other line extensions pertaining to a special operator's position for uniting lines in conversation and in interchangeable association with the incoming ends of telephone lines to effect the extension of these lines; special operator's responsive devices individual to and permanently associated with telephone lines; and means controlled by the regular operator for operating said responsive devices independently of the connecting ends of the line extensions under her control and by way of the incoming ends of the telephone lines.

31. A telephone exchange system including telephone lines extending to an exchange; line extensions for uniting lines in

conversation; electro-magnetic switches for effecting the interchangeable association of the line extensions with the incoming ends of telephone lines to effect the extension of these lines to a regular operator's position; other line extensions pertaining to a special operator's position for uniting lines in conversation and in interchangeable association with the incoming ends of telephone lines to effect the extension of these lines; special operator's responsive devices individual to and permanently associated with the telephone lines; and means controlled by the regular operator for operating said responsive devices independently of the connecting ends of the line extensions under her control and by way of the incoming ends of the telephone lines.

In witness whereof, I hereunto subscribe my name this eleventh day of January A. D., 1915.

ELMER R. CORWIN.

Witnesses:

G. L. CRAGG,
ETTA L. WHITE.
